UNITED STATES PATENT OFFICE.

CLARENCE E. PRYOR, OF JERSEY CITY, NEW JERSEY, ASSIGNOR TO JENNIE A. SWEAF,
OF NEW YORK, N. Y.

BUMPER.

Application filed May 20, 1922. Serial No. 562,320.

To all whom it may concern:

Be it known that I, CLARENCE E. PRYOR, a citizen of the United States of America, residing at Jersey City, county of Hudson, State of New Jersey, have invented certain new and useful Improvements in Bumpers, of which the following is a specification.

This invention relates to bumpers.

More particularly this invention relates to bumpers embodying a plurality of rails, arranged in different vertical planes relative to the car and assembled relative to one another to provide for resilient resistance in opposition to encountering obstacles effected as a resultant by the combination of the resiliencies of the individual rails.

A further feature of the invention is the provision of mounting means for the plurality of rails whereby the front faces of the rails are maintained normally and when encountering an obstacle in substantial parallelism and substantially in vertical planes.

A further feature of the invention is the provision of improved means for the combined inter-tying of the rails to provide for relative movement of the rails to one another when encountering an obstacle and thereby give rise to an improved resultant resiliency.

Pursuant to a preferred form of the invention, two rails are located forwardly of and respectively above and below a rearward central rail; the rearward rail is mounted in a pair of spaced clips and the clips are yieldingly and adjustably mounted on the spring horns of the automobile or other vehicle whereby the rearward rail is maintained substantially vertical for all positions of yielding of the clips, and the forward rails are intertied with one another and with the rearward rail whereby in the event of an obstacle encountering the forward rails at any location between the spring horns the rearward rail is automatically moved forwardly in combination with the forward rails to increase the resistance of the forward rails in opposition to the encountering obstacle and to present the rearward rail in opposition to the obstacle, such movements being effected with the elimination automatically of all thrusts and strains on the spring horns towards or away from one another; and whereby in the event

of an obstacle encountering any end portion of a forward rail laterally of a spring horn, the opposite end portion of such rail operates in combination with the other forward rail and with the rearward rail and is moved automatically forwardly to thereby increase combinedly the resistance of such encountered end portion of the rail in opposition to the obstacle and automatically eliminating all thrusts and strains on the spring horns towards or away from one another.

Further features and objects of the invention will be more fully understood from the following detail description and the accompanying drawings, in which—

Fig. 1 is a top plan view of a bumper embodying three rails, two of which are normally located in advance of the third rail, the same being mounted on the forward pair of spring horns of any approved type of automobile and arranged pursuant to my invention;

Fig. 2 is a front elevation of the arrangement shown in Fig. 1;

Fig. 3 is a detail vertical central elevation on line 3—3 of Fig. 1, on an enlarged scale;

Fig. 4 is a sectional elevation on line 4—4 of Fig. 3;

Fig. 5 is a detail side elevation as viewed on line 5—5 of Fig. 1, on an enlarged scale;

Fig. 6 is a detail front elevation of a forward pivot member, shown in Fig. 5;

Figs. 7 and 8 are respectively a side elevation and plan view of an intermediate keeper member, shown in Fig. 3, on an enlarged scale;

Figs. 9 and 10 are respectively detail front elevation and top plan view, of a modification, illustrating a different form of intertying of the ends of the bumper rails;

Fig. 11 is a detail plan view of a modified rail;

Fig. 12 is a modification of Fig. 1, showing a common pivot rod replacing separate pivot pins of the respective rail-carrying clips;

Fig. 13 is a detail vertical sectional view showing a modification of rail-carrying clip;

Fig. 14 is a side elevation similar to Fig. 5, but showing a modified form of resilient means for resisting backward movement of

the bumper bars and further improved means for mutually locking the nuts of the spring holding bolt and clip retaining bolt against displacement by jarring or vibrations;

Fig. 15 is a rear elevation of the nuts of the spring-holding bolt and clip-retaining bolt and the mutual nut locking arrangement;

10 Fig. 16 is a rear elevation similar to Fig. 15 but showing a modification;

Fig. 17 is a top plan view of the center rail shown in Figs. 9 and 10 but showing a modified form of composite rail sections tied centrally by an improved form of clip;

Fig. 18 is a central transverse sectional view of Fig. 17; and

Fig. 19 is a detail front elevation on an enlarged scale of the centrally-tying clip.

20 Referring to Figs. 1, 2 and 5, the particular embodiment of the invention as illustrated in the drawings comprises the upper forward rail 10, the lower forward rail 11 and the central, rearward rail 12. Such forward rails 10, 11 may be interconnected centrally by means of the strap 14, having its upper end bent about the upper edge of the upper rail 10 and its lower end bent about the lower edge of the lower rail 11 and carrying centrally the plate 14^a, secured thereto by the vertically aligned screws 14^b. The front face of the plate 14^a may be marked with a designation of the manufacturer, or to indicate any particular style of bumper or be ornamented by an emblem or otherwise to suit the fancy of the purchaser.

40 Such plurality of rails are movably inter-tied with one another by the opposite end inter-tying means 15, 16. The rails are supported by means of the spaced members 17, 18, carried respectively by the spring horns, 19, 20 of the automobile or other type of vehicle.

45 Each mounting member 17, 18, see Fig. 5, comprises the rail carrying clip 21 formed as a vertical U and having the clearance 22 within which the rail 12 is received and locked therein by means of the screw 23, bolt or the like. The rearward portion 24 of each member 17, 18, extends integrally from the clip member 21, and comprises a flat central upper face 24^a and a rearward extension provided with the intermediate slot 25 and oppositely disposed fork elements 26, 27. The lower portion 28 of each member 18 is hollowed to movably receive therein the forward pivot member 29, pivoted at its upper end on the pin 30 and at its lower end on the relatively long, stout pin 31.

60 As will be noted in Fig. 5, the retractile coil spring 32 has its upper hooked end 33 hung on the pin 30 and its lower hooked end 34 secured to the pin 35 extending from one lug 36 to its opposite lug 36, see Fig. 2.

65 At the upper rearward portion of each

mounting member 17, 18 is secured the pin 37 which is removably mounted in the oppositely disposed fork members 26, 27 and extends across the intermediate slot 25. The eye bolt 38 has its eye 39 lodged on the pin 37 and the opposite eye 40 of the eye bolt 38 is secured to the pin 41 of the pair of pivot lugs 42. The eye bolt 38 is preferably arranged to be adjustable in length by means of the sleeve 43 provided with a continuous threading, say of right-hand turn, meshing with the right-hand threadings 44, 45 on each of the ends of the separable parts 38^a, 38^b of the eye bolt 38, see Fig. 5.

70 Preferably, the pair of pivot lugs 36, 36 for the pin 35, the pair of pivot lugs 46, 46 for the pin 31 and the pair of pivot lugs 42, 42 for the pin 41, are cast integrally with the base member 47, which is secured to the spring horns 19, 20 respectively, by means of the rearward set bolts 48, 48', and locked forwardly by the hooked end 49.

75 The set bolts 48, 48' are preferably locked by means of the plate 50 having a curvature greater than the spring horn 20 and provided with a circular opening 51, through which extends the bolt 48 and further with a slotted opening 52 through which extends the bolt 48'.

80 The adjustment of the adjustable eye bolt 38 is attained by removing the pin 37 to free the eye 39 of the bolt 38 and turning the collar 43 to attain increased or decreased spacing of the separable parts 38^a, 38^b of the bolt 38. By the provision of the right-hand threadings 44, 45 of the separable parts 38^a, 38^b of the bolt 38 any movement of the threaded collar 43 due to vibration, jarring or the like will not cause any variation in the effective length of the eye bolt 38.

85 As indicated above, the extreme ends of the rails 10, 11, 12 are inter-tied by the inter-tying members 15, 16, the construction of which is similar, and accordingly a detail description of one of said members, to wit, 15, as is illustrated in Figs. 3 and 4 will suffice to describe the other inter-tying member 16; like reference numbers are employed to indicate like parts of the members 15, 16.

90 Referring to Fig. 1, the upper forward rail 10 extends for its major portion, substantially rectilinearly and substantially at right angles to the longitudinal center line of the vehicle, but at the oppositely disposed location 53, 53 is bent rearwardly as is indicated at 54 toward the respective inter-tying members 15, 16. The inter-tying members 15, 16 substantially lie normally in the plane of the substantially rectilinear, central, rearward rail 12. The lower, forward rail 11 is arranged similarly to the upper, forward rail 10.

95 Referring to Fig. 3, the extreme end of the upper rail 10 is substantially in vertical alignment with the extreme end of the cen-

tral rail 12 which in turn is in substantially vertical alignment with the extreme end of the lowermost rail 11. As has been indicated above, the oppositely disposed means 15, 16 are provided for respectively inter-tying the ends of the upper rails 10, 11 and the central rail 12 to one another whereby to provide for movement of the rails relative to one another and to effect in the event 10 of encountering an obstacle a resultant resiliency arising from the combined action of the rails relative to one another and the elimination of thrusts or strains on the spring horns toward or away from one another.

As one form of such inter-tying means, 15, 16, I provide, as is illustrated enlarged in Fig. 3, the slotted sleeve 55 extending from above the uppermost rail 10 to below the lowermost rail 11, the slot thereof being indicated at 56—56 and of a normal clearance, as is indicated in Fig. 4, substantially equal to the thickness of any rail 10, 11, 12. Between the central and the respective 25 upper and lower rails are disposed the spacing and keeper members 57, see Fig. 3, each comprising an outwardly extending circular apron 58, an inwardly disposed, circular lock portion 59 connected integrally by the extension 60, see Fig. 8, with the outer apron 58; the extension 60 is substantially the width of any rail 10, 11, 12 whereby there is provided an annular slot 61 extending a full circumference excepting 30 for the width of the extension 60. Within such slot 61 is located the slotted sleeve 55. On the upper face of each keeper member 57 is provided a substantially rectilinear, diametrically extending rib 62 and similarly 35 on the lower face is provided a substantially rectilinear, diametrically extending rib 63. Coacting with the upper rib 62 of the upper keeper member 57 are means for connection with the uppermost rail 10 namely in the 40 form of the slot 64 at the lower edge of the uppermost rail, and similarly there is provided in the upper edge of the central rail 12 the slot 65 for coaction with the lower rib 63 of the upper keeper member 57.

Similarly, for the lower keeper member 57, I provide the slot 66 at the lower edge of the central rail 12 for coaction with the upper rib 62 of the lower keeper member 57 and likewise the slot 67 at the upper edge of the lowermost rail 11 for receiving the lower rib 63 of the lower keeper member 57.

The top keeper member 68 corresponds in construction to the aforesaid intermediate keeper members 57 and like parts are 60 marked with the same reference numbers; however, the top keeper member 68 extends integrally, as is indicated at 69 for the full diameter of the lock portion 59 to thereby fill the space within the hollow cap 70 threaded to the upper threaded end 71 of

the hollow sleeve 55; its rib 63 on its lower face is received within the slot 72 at the upper edge of the uppermost rail 10.

The bottom keeper member 73 corresponds in construction to the top keeper member 68 but is of obverse disposition; the rib 74 on its upper portion is received within the notch 75 at the lower edge of the lowermost rail 11 and the lower face 76 extends integrally of its lock portion 59, to 75 fill the interior of the bottom cap 77 threaded to the lower end 78 of the slotted sleeve 55.

The left-hand inter-tying means 16 corresponds in construction to the right-hand inter-tying means 15 and like parts are indicated by the same reference numbers.

As an additional means for serving as a rail and further coacting with the spaced clips 21 and mounting means therefor, including the base plate 53 attached to the respective spring horns 19, 20, I provide the rod 80 having the nuts 81, 82 at its opposite ends, see Fig. 1, and passing through the openings 83, see Fig. 5, in the 90 respective base plates 53, 53.

In the event of the bumper, shown in Figs. 1 to 5 inclusive, encountering an obstacle say at the extreme right-hand free portion of the forward rails 10, 11, the forward rails will be flexed rearwardly to the position 10^a indicated in dot and dash outline in Fig. 1, in which action the rearward rail 12 at its free right-hand end is flexed to the position 12^a indicated in dot and dash outline, due to the inter-tying means 15. The position assumed by the inter-tying means 15 is indicated at 15^a. Such rearward flexing of the aforesaid right-hand parts causes the flexing forwardly of the 100 left-hand free end portions of the upper forward rail 10 to the position 10^b, and similarly the lower forward rail 11, and the rearward rail 12 will be flexed forwardly to the position 12^b indicated in dot and dash outline due to the inter-tying means 16, the inter-tying means being moved forwardly 110 to the position indicated at 16^b.

As a result of such mutual coaction, the resiliency of the right-hand free end of the rails struck by the obstacle, is increased, resulting in an increased opposition of the struck rail or rails to the obstacle. The degree of increase of the opposing resiliency increases with the extent of flexing of the 120 struck rail from normal position.

Furthermore, such coaction of the rails with one another, is effected without any thrust or strain in the central portion of the rearward rail 12 and without any thrust or strains on the clip members 17, 18, toward or away from one another and thereby relieving the spring horns 19, 20 from all thrusts or strain laterally toward or away 125 from one another.

In the event of an obstacle encountering any rail at a central portion thereof, that is to say between the spaced clips 17, 18, by reason of the inter-tying of the front rails 5 with the rearward rail as above described, the front rails recede bodily in a substantially parallel movement toward the rearward rail and upon continued recession of the forward rails the rearward rail is 10 brought in vertical alignment with the forward rails to present additional opposition to the obstacle. Such parallel movement of recession of the forward rails bodily causes a corresponding recession of the opposite 15 inter-tying means 15, 16, without giving rise to any strain or thrust on the spring horns toward or away from one another.

It will be noted that in the event of any rail encountering an obstacle, the impact 20 gives rise to a receding of the rails bodily in addition to the yielding afforded by the extent of receding being dependent upon the resistance of the springs 32, 32, of the respective clips. It will be further noted that 25 upon recession of the rails, by reason of the mounting means of the respective clips 17, 18 on the sets of parallelly arranged pivotal members 29, 38, the rails are elevated with respect to the spring horns and at the 30 same time the front faces of the rails are maintained substantially vertically.

Preferably, the center rail 12 as shown in Fig. 11, comprises a plurality of rails 89 of graduated increasing lengths extending 35 respectively centrally between and laterally of the clips 17, 18 thereby providing for increased resistance between the clips 17, 18, and also for a graduated increasing resistance 40 against flexing rearwardly when an obstacle encounters either free end portion of the rails, as is indicated in Fig. 11.

For the purpose of adjusting the effective 45 length of the eye-bolt 38, either eye 39, 40 is freed of its pivot pin, by withdrawing such pivot pin thereby permitting change in length of the eye-bolt as may be desired, by turning any one of the two parts, 38^a, 38^b, see Fig. 5, with the collar 43, and holding the other part stationary. The 50 removed eye is then reassembled on its pin. For the purpose of preventing the collar from being freed from either of the eye-bolt parts 38^a or 38^b, the length of threading on the inner face of the collar 43 is made 55 longer than the sum of the lengths of the two right-hand threadings on the eye-bolt parts 38^a, 38^b, whereby when the eye-bolt parts are reasonably close to one another and the collar even if turned for the full 60 length of the threading on one of its bolt parts, engagement with the threading of the other eye-bolt part is maintained and uncoupling precluded. If desired, one eye-bolt part may be permanently secured to the 65 collar 43.

It will be noted from Figs. 6 and 5 that each pivotal member 29 provides for an area of bearing of large magnitude for its pin 31 and an extended area of bearing of the re-inforcing bosses 88 for its pin 30, and the wide lateral faces of each pivotal member 29 in engagement with its respective sets of pivot lugs, prevents lateral swaying of the clips 17, 18, and of the rails, and precludes audible vibrations. 70 75

Another modification of inter-tying of the ends of the rails is shown in Figs. 9 and 10, wherein the upper rail 10, as is indicated in Fig. 9, is bent at a location indicated generally at 90 rearwardly until such end portion of the rail 10 assumes a substantially horizontal position as indicated at 91. In a similar manner, the lower forward rail 11 is bent upwardly at the location indicated generally at 93 and rearwardly until such end portion of the rail 11 assumes a substantially horizontal position as indicated at 96. 80 85

As is indicated in Fig. 10, the central rail 12 at each of its opposite ends is bent on itself as is indicated at 97 to form an eye, preferably located on its rearward flat face. Between the flat face 91 of the upper forward rail 10 and the eye 97 of the central rail 12 is disposed the spacing collar 98 and between the eye 97 of the central rail 12 and the horizontal flat face 96 of the lower forward rail 11 is disposed a similar collar 99 and the bolt 100 is passed through a suitable opening in the flat face 91 of the upper rail 10, thence through the collar 98, thence through the eye 97 of the central rail 12, thence through the collar 99 and thence 95 through a suitable opening in the horizontal flattened portion 96 of the lowermost rail 11; the bolt 100 is locked and tightened in 100 position by the nuts 101, 102 at its opposite threaded ends. 105

The inter-tying action at the opposite ends of the rails 10, 11, 12 in the arrangement shown in Figs. 9 and 10 is similar to that described hereinabove. The arrangement of Figs. 9 and 10 is simpler in assembly and derives an enhanced resistance provided for by the bending of the top rail 10 and bottom rail 11. 110 115

In the modification shown in Figs. 9 and 10, the co-action of the respective rails, and the upward, parallel movement of the rails bodily by reason of the parallel pivotal means of the respective clips, is similar to that described relative to the construction shown in the preceding figures. 120

In any of the modifications shown hereinabove, the clips 17, 18 are held in their normal lowermost position by any suitable means, as by means of the respective forward link members 29, 29 of the respective clips 17, 18. As will appear from Fig. 5, each forward link member 29 is provided 125 130

- with the relatively flattened face portion 105, see Figs. 5 and 14, disposed eccentrically beyond the axis of its pivot pin 31 whereby when the rails are free, such faces 105 encounter the upper faces of the base plates 53, 53 respectively, thereby limiting the downward movement of the link members 29 and therewith limiting the downward movement of the clips 17, 18. The adjustment of the eye-bolt 38 as above described, is provided primarily to attain substantially vertical positioning of the front face of the rearward rail 12, and likewise of the forward rails 10, 11 when the surface portions 105 of the respective link members 29, 29 are in engagement with the base members 53, 53. If desired, the pins 31 of the respective pivot members 29 may be replaced by a common pivot rod 31^a, see Fig. 12, making a tight connection by means of a spline, key, weld or polygonal cross-section respectively with the pivot members 29 of the spaced bumper-carrying clips 21, whereby upon displacement of any portion of any bumper rail and consequent upward rotation of either pivot member 29, the other pivot member 29 is to like extent rotated upwardly by reason of such rigid connection with such common pivot rod and thereby bringing into simultaneous action both springs 32 and relieving the bumper parts of twisting or binding.
- Such common pivot rod serves also as a tie rod and a barrier.
- In Fig. 13, I illustrate a modified form of clip for horizontally pivotally carrying one bumper rail 12 or a plurality of bumper rails 12, 89, and comprising a yoke 110 exteriorly embracing the rail 12 or rails 12, 89 on the vertical frontal face and horizontal upper and lower faces and further embracing a bulge member 111, the latter being pivoted jointly with the yoke 110 to the common pivot bolt 112 passing through the vertical opening 113 in the clip 24. Upon tightening the bolt 112, the bulged member 111 is forced forwardly into compressional contact with the rail or rails 12, 89, thereby clamping the same with the yoke 110.
- In Fig. 14, I illustrate a modified form of spring arrangement for resisting rearward displacement of the bumper rails, comprising an extension 114 having an opening 116^a for attachment to one end of the spring 115; the other end of the spring 115 is hooked in the eye of the eye-bolt 116, adjustably anchored on the axle 117 of vehicle. Such anchoring means comprises a hook member 118 and a co-acting hook bolt 119 passing through an opening 120 in the back plate 121. The spring holding bolt 116 passes through the opening 122 in the back plate 121. As is indicated in Fig. 14 and also in Fig. 15, the openings 120, 122 are arranged on centers spaced from one another less than the sum of the maximum radius of the nuts 123, 124, respectively of the spring-holding bolt 116 and the hook bolt 119. Such arrangement precludes turning of the nuts 123, 124 by mutual engagement with one another, under the condition of jarring incident to traveling but upon the spring-holding bolt 116 being forcibly drawn rearward to clear its nut 123 from engagement with the nut 124.
- In a similar manner, the rearward end of the spring 115 may be secured to the car-spring 117^a, or any suitable part of the car.
- In Fig. 16, the back plate 121 is offset at 125 to afford a locking shoulder thereto for the nut 123 of the spring-holding bolt 115.
- In Figs. 17, 18 and 19, the rail 126 is formed of a forward integral portion extending from one free end to the opposite free end of the rail and is bent forward on itself, the ends being indicated at 127, 128 respectively and providing a clearance 129 therebetween. The front rail 130 is located forward of the rail 126 and held in the rail-holding clips 110. The central tying clip 131 passes over the frontal face of the rail 130 and over the upper and lower edges of the rail 130, the rail 126 and its forwardly bent end portions 127, 128, and receives in its upper and lower openings the bolt 132 rivet or the like, passing through the clearance 129, and thereby locks the ends 127, 128.
- From the above several embodiments of my invention, it will be observed that my invention provides for an arrangement of multiple bumper rails arranged to preclude rattling and of relatively light weight and when struck by an obstacle to provide for an increased degree of resiliency and strength against rupture and also relieving the fixed parts of the car from undue strains. The provision of the mutual resilient relation of the bumper rails with one another and combined with the displacement resisting springs sets up a resistance against displacement of the rails in the event of encountering an obstacle, in a proportion materially more rapidly than the extent of displacement of the struck rail. Such improved action ensues by reason of the paths of travel of the bumper rails being disposed at a constantly increasing angle to the path of distension of the displacement resisting springs.
- Whereas I have described my invention by reference to specific forms thereof it will be understood that many changes and modifications may be made without departing from the spirit of the invention.
- I claim.
1. The combination with the spring horns of an automobile or the like, of a bumper rail, a clip normally holding said rail to present a face thereof substantially vertical and means for yieldingly mounting said rail

- on said spring horns to provide for substantially parallel vertical movement of said rail for different positions of yielding of said rail.
5. 2. The combination with the spring horns of an automobile or the like, of a bumper comprising a plurality of rails arranged in different vertical planes, a plurality of spaced clips normally holding said rails to 10 present a face thereof substantially vertical and means for yieldingly mounting said rails on said spring horns to provide for substantially parallel vertical movement of said rails for different positions of yielding 15 of said rails.
3. The combination with the spring horns of an automobile or the like, of a bumper comprising a plurality of bumper rails, a plurality of spaced clips normally holding 20 said rails to present a face thereof substantially vertical and resilient means mounted respectively fixedly on said spring horns to provide for substantially parallel vertical movement of said rails for different positions of yielding 25 of said rails.
4. The combination with the spring horns of an automobile or the like, of a bumper rail, a clip normally holding said rail to present a face thereof substantially vertical and means for yieldingly mounting said rail on said spring horns to provide for substantially parallel movement of said rail for 30 different positions of yielding of said rail, said mounting means comprising a pair of pivotal links mounted for movement in substantially vertical planes.
5. The combination with the spring horns of an automobile or the like, of a bumper comprising a plurality of rails arranged in 40 different vertical planes, a plurality of spaced clips normally holding said rails to present a face thereof substantially vertical and means for yieldingly mounting said rails on said spring horns to provide for substantially parallel movement of said rails for different positions of yielding of said rails, said mounting means comprising a pair of pivotal links mounted for movement in substantially vertical planes.
50. 6. The combination with the spring horns of an automobile or the like, of a bumper comprising a plurality of rails arranged in different vertical planes, a plurality of spaced clips normally holding said rails to 55 present a face thereof substantially vertical and resilient means mounted respectively fixedly on said spring horns to provide for substantially parallel vertical movement of said rails for different positions of yielding 60 of said rails, said mounting means comprising a pair of pivotal links mounted for movement in substantially vertical planes.
7. The combination with the spring horns of an automobile or the like, of a bumper comprising a plurality of rails, a plurality 65 of spaced clips normally holding said rails to present a face thereof substantially vertical and resilient means mounted respectively fixedly on said spring horns to provide for substantially parallel movement of said rails for different positions of yielding of said rails, said mounting means comprising a pair of pivotal links mounted for movement in substantially vertical planes.
- of spaced clips normally holding said rails to present a face thereof substantially vertical and resilient means mounted respectively fixedly on said spring horns to provide for substantially parallel movement of said rails for different positions of yielding of said rails, said mounting means comprising a pair of pivotal links mounted for movement in substantially vertical planes, and supporting means comprising a plurality of pivot members disposed at spaced locations on said rearward rail. 70
8. The combination with a bumper rail, of a clip for removably supporting said rail and means for supporting said clip on a fixed portion of a vehicle to provide for upward movement of the rail in the event of encountering an obstacle, said clip supporting means comprising a pair of substantially parallelly arranged links. 75
9. The combination with a bumper rail, of a clip for removably supporting said rail and means for supporting said clip on a fixed portion of a vehicle to provide for upward movement of the rail in the event of encountering an obstacle, said clip supporting means comprising a pair of substantially parallelly arranged links, one of said links being adjustable in length for the purpose of setting the rail in a predetermined position. 80
10. The combination with a bumper rail, of a clip for removably supporting said rail and means for supporting said clip on a fixed portion of a vehicle to provide for upward movement of the rail in the event of encountering an obstacle, said clip supporting means comprising a pair of substantially parallelly arranged links, one of said links comprising a plurality of members arranged in longitudinal alignment and provided with threading of the same sense of direction and an interconnecting member in threaded relation with one or more of said threaded members. 85
11. The combination with a bumper rail, of a clip for removably supporting said rail and means for supporting said clip on a fixed portion of a vehicle to provide for upward movement of the rail in the event of encountering an obstacle, said clip supporting means comprising a pair of substantially parallelly arranged links, one of said links comprising a plurality of members each provided with an eye at their opposite ends, said members being arranged in longitudinal alignment and provided with threading of the same sense of direction and an interconnecting member in threaded relation with the aforesaid plurality of threaded members. 90
12. In a bumper, a clip for a bumper rail comprising a member provided with a recess for receiving a rail, means for pivotally supporting said recessed member on a 115
- 130

- fixed part of a vehicle, said pivotal means comprising an element provided with a longitudinal slot and a spring disposed in said slot and having its one end secured fixedly 5 relatively to the vehicle and its other end secured fixedly relative to said recessed member.
13. In a bumper for a spring mounted vehicle, having a spring horn, a clip member 10 provided with a recess for receiving a bumper rail, a pair of links arranged in vertical plane for supporting said clip member, a base member, means for pivotally securing said links to said base member and means 15 for attaching said base member to a spring horn of the vehicle.
14. In a bumper for a vehicle, a rail, means for supporting the rail on the vehicle to provide for upward movement of the rail 20 in the event of the same encountering an obstacle, said supporting means comprising a plurality of spaced pivot members and pivot means connecting said spaced pivot members rigidly relatively to one another.
15. In a bumper for a vehicle, a rail, a pair of spaced pivot members carrying said rail, means for mounting said pivot members on the vehicle to provide for substantially vertical movement thereof and horizontally extending means fixedly connecting said pivot members relatively to one another. 25
16. In a bumper for a vehicle, a rail, a plurality of arms secured to said rail at spaced locations thereof, and means for pivoting said arms respectively to provide for vertical movement of said arms, said pivoting means comprising a horizontally extending element fixedly connecting said arms 30 relatively to one another.
17. In a bumper for a vehicle, a rail, a plurality of arms secured to said rail at spaced locations thereof, means for pivoting said arms respectively to provide for vertical movement of said arms, said pivoting means comprising a horizontally extending element fixedly connecting said arms relatively to one another, and displacement resisting springs connecting said arms respectively to a fixed portion of the vehicle. 35
18. In a bumper for a vehicle, a rail, a plurality of arms secured to said rail at spaced locations thereof, means for pivoting said arms respectively to provide for vertical movement of said arms, said pivoting means comprising an element provided with a longitudinal slot and a spring disposed in said slot and having its one end secured fixedly relatively to the vehicle and its other end secured fixedly relative to said recessed member. 40
19. In a bumper for a vehicle, a rail, a plurality of arms secured to said rail at spaced locations thereof, means for pivoting said arms respectively to provide for vertical movement of said arms, said pivoting means comprising an element fixedly connecting said arms relatively to one another, displacement resisting springs connecting said arms respectively to a fixed portion of the vehicle, and means for securing one end of each of said springs respectively to the vehicle, said securing means comprising a plate provided with openings, a plurality of bolts passing through said openings and nuts for said bolts, the dimension of spacing of said openings relative to the dimensions of said nuts providing for mutual engagement of said nuts to prevent unloosening of said nuts. 45
20. In a bumper for a vehicle, a rail, a plurality of arms secured to said rail at spaced locations thereof, means for pivoting said arms respectively to provide for vertical movement of said arms, said pivoting means comprising an element fixedly connecting said arms relatively to one another, displacement resisting springs connecting said arms respectively to a fixed portion of the vehicle and means for securing said springs to the vehicle, said securing means comprising a plate having an offset portion and an opening adjacent said offset portion, a bolt passing through said opening and a nut for said bolt contacting with said offset. 50
21. In a bumper, a rail, securing means for said rail and means for pivoting said securing means to the vehicle, said securing means comprising a yoke having pivot openings, a locking member surrounded by said yoke and engaging said rail when said yoke is secured to the vehicle by said pivoting means. 55
22. In a bumper for a vehicle, a rail and means for supporting said rail on the vehicle, said supporting means comprising a yoke engaging said rail on one face, a clamping member enclosed by said yoke and engaging said rail on an opposite face, said yoke and said clamping member being provided with openings and a pivot pin passing through said openings thereby clamping said yoke and said clamping member onto said rail. 60
- In testimony whereof I have signed this 7th day of March 1922. 65

CLARENCE E. PRYOR.
